SHOE HOLDER

David W. Tibbott, Newton, Mass., assignor to
 Whittemore Bros. Corp., Cambridge, Mass., a
 corporation of Massachusetts

Application December 11, 1935, Serial No. 53,909

4 Claims. (Cl. 12—128.1)

This invention relates to improvements in shoe holders.

More particularly it relates to devices for holding firmly a shoe which is undergoing surface treatment, holding it rigidly in various different positions while its surface is being cross-rubbed, as when being polished, dyed, whitened, or otherwise treated with a dressing while held in one hand of a person who is performing the operation with his other hand.

For perfect execution and complete treatment of all parts of the surface it is desired that the device should hold the shoe firmly; and that the leather or other flexible and yielding material of the shoe be supported rigidly against the brush-rubbing. For a maximum of convenience and speed it should also be held so that the shoe can be held up in the air and be turned at various angles and directions, according to the particular part of the surface which is being treated.

The invention provides a device for such a holding of the shoe. It is an object to provide so that a person can with one hand hold the shoe rigidly down on a bench, table or other firm support; or can hold it up in any of various convenient positions, free from all support except that of his one hand, with a local backing of all necessary parts of the flexible material of the shoe, sufficiently firm for the polishing.

Other objects are to accomplish this with a device which is so light in weight as to be not burdensome to the operator; one which can fit shoes of differing shapes and sizes; and one which can be made at low expense as regards material and cost of manufacture.

It is a further object of the invention to make the article, which can serve all of these functions, by a stamping and a manipulative bending of sheet metal.

For accomplishing these varied aims in one unitary article, the invention provides for the making of a hollow cylindrical sheet metal handle, large enough to be firmly and comfortably grasped. This will stand horizontal, or at an angle near the horizontal, when the shoe which it is holding rests with heel and sole on a horizontal surface. From the forward end of this handle a stiff strut extends downward and forward, obliquely, with suitable curvature out toward the toe, having sections spreading laterally from its median line and curved downward laterally to afford support for the vamp and toe against the pressure of a brush rubbing on the exterior. From the rear end of this handle another strut extends downward and slightly back-

ward, and presses backward, to engage the counter near the sole, as by a prong, or by a friction-button of rubber, or by a spread. This rear strut may have elasticity strong enough to hold the shoe by its backward pressure at that point. This strut, based on the handle, may be integral therewith, or may be a separate spring bar fastened thereto, but the inclination of this strut from the vertical is so slight that a stiff downward pressure can be exerted on it, downward from the handle, without bending it.

Thus, by one's downward pressure on the handle, the shoe can be held rigidly down in frictional engagement on the bench, at toe and heel; and this is a position in which transverse thrusts of the brush can be resisted by the bench as well as by the hand of the operator. The shoe can also be held firm by the hand of the operator alone, when lifted in air, without the aid of the bench; and in each position it can be conveniently manipulated to receive the rubbing of the brush and to be inspected in all parts of its surface.

The material and the manipulation for constructing this article are simple, being stamped of sheet metal, bent by simple operations.

It is intended that the patent shall cover, by suitable expression in the appended claims, whatever features of patentable novelty exist in the invention disclosed.

In the accompanying drawing:

Figure 1 is a plan of a plane blank of sheet metal, suitable for being formed into a shoe holder embodying features of the invention;

Figure 2, on a larger scale, illustrates a shoe holder made from a blank of sheet metal such as is portrayed in Figure 1, and a shoe being indicated by dot and dash lines in position held on the shoe holder;

Figure 3 is an elevation of the shoe holder of Figure 2, looking from the left in Figure 2, being the toe end;

Figure 4 is an elevation of a fragment of a rear strut, similar to that of Figure 2, but having a modified form of counter-engaging means, a portion of the strut being broken away to show the counter-engaging means in medial section.

Figure 5 is an elevation, in medial section, showing a bar spring, with attached handle, each down-turned end of the spring being secured to a strut, of which a fragment is shown;

Figures 6 and 7 illustrate a detachable securing of bar spring to a strut.

Referring to the drawing, the blank of Figure 1 may be of any suitably stiff sheet metal capable

of being formed, by bending, into the shoe holder shape shown in Figures 2 and 3. The rectangular mid-part 10 of the blank provides the stock for a tubular hand grip portion 10', the side edges 5 of the part 10 being brought around to approach contact with each other, as seen in Figure 3. The simple and low-cost formation illustrated in Figure 3 is adequate and effective; but these edges may be brought together, if desired, and may 10 be secured together as by solder or by spot welding, thus making ample stiffness and strength from thin stock.

The fore strut 12, 14, 16, of the blank has stock for supporting lateral parts of the toe box and 15 vamps of a shoe. Both of these parts 12, 14 have limbs extending broadly to each side of the median line of the blank, bent downwardly with slightly arcuate cross section as at 12', 14' and 16' in Figures 2 and 3. The forepart 12 and the 20 part 14 are formed to fit their respective parts of a shoe, the part 12 being shaped to constitute a toe support 12' and the part 14 being made to have an arcuate cross section for supporting the vamps at the instep portion of a shoe as at 14', 25 while the part 16' may be merely a strut, extending obliquely forward from the handle 10', whose slight cross curvature makes it unbendable.

At the rear end of the hand grip 10', a second strut 18' extends downward, and has a stiff part 30 18' and a part 20' with lateral curved limbs, for standing within the counter of the shoe at its extreme rear. The strut 18' 20' is formed from the parts 18, 20 of the blank. It is bent downward at its juncture with the hand grip as is the 35 forward strut 16, but this rear strut may extend nearly perpendicular to the hand grip or, preferably, with slight inclination from the vertical.

In one form, a prong 22' is provided at the lower end, for securely engaging the shoe counter 40 as seen in Figure 2. In Figure 1 this is seen at 22 at the outermost edge of the part 20 of the blank.

Another form, seen in Figure 4, employs a friction button 22'' for engaging the shoe counter 45 at the rear.

Still another form, seen in Figure 7, has the wings of the strut spread, and made of resilient material, so that they can engage within both 50 sides of the counter simultaneously.

The portions 17, 19 of the blank provide resilient strip portions 18' and 19' immediately adjacent to the handle, one at each end thereof, for continually urging the parts 12', 14' and the 55 part 20' against their respective portions of the shoe.

In Figure 5, a separate spring element 24 is 60 suitably secured to handle 26 and reaches outward and downward from the handle, being downturned at each end to be secured respectively to the fore strut and to the rear strut.

If the stock 12', 14' is thin enough to be readily flexible it may be of elastic nature so as to bend laterally, more or less according to shoe size and shape. This can be so, because the fore and aft 65 stiffness and elasticity can be provided by the bent bar spring 24 which extends through the handle and re-enforces the top part of each said strut.

If desired, the fore strut, comprising the parts 70 12', 14' and 16' or the rear strut 18', 20', or both of them, may be separable from the handle, to permit of substitution of other struts of size and shape to fit particular sizes and styles of shoe; 75 or to permit compact packing of the holder. Fig-

ures 6 and 7 illustrate a simple form of separable attachment wherein the spring 24' has its end part sticking through a cross slot in the strut, from the outer side, with the offset tip end 24'' of the strut engaging the strut on its inner side. 5 The strut in turn has a terminal lug 16a sticking through a cross slot 24''' in the spring from its inner side. By this means the fastening of handle to strut is adequately secured for all ordinary uses of the holder, and yet the parts may be 10 quickly and easily separated.

Figure 7 shows also a lower end of strut 20'' designed for the spread engagement within a shoe, there being sufficient stiffness for accomplishing the strut function, and the spread sides 15 of the strut having a degree of springiness whereby they can engage simultaneously the opposite sides of the shoe interiorly.

The forward and the rear struts thus tend to 20 spread apart, when set within a shoe, but the rear one may be pressed a little forward to facilitate the insertion of the device into a shoe, or its removal thence. When within, their resilient spreading makes secure engagement of the shoe 25 at front and rear. By the hand grip 19' one can then conveniently grasp the shoe, in effect, with one hand, and can press the shoe firmly against a bench or the like, while rubbing with the other hand, or can hold the shoe in air by one hand for treating any part of its surface conveniently 30 by the other hand.

The holder supports those thin parts of the shoe upper which naturally would yield under the pressure of a brush. It can accommodate a wide 35 variety of sizes and styles of shoes, yet is low in cost to produce and is of enduring character.

I claim as my invention:

1. A shoe holder made from a stiff sheet fore-part, comprising a forepart fashioned to fit the toe of a shoe and having adjacent thereto a 40 curved sheet for supporting the vamp at the portions which extend toward the instep, and having an in-thrusting part with a portion which is curved in cross-section; a stiff sheet rear part with a portion which is curved in cross-section 45 for engaging simultaneously with pressure two side portions of the shoe within the counter, and having an up-reaching part; and a stiff handle secured to and between the said in-thrusting part and up-reaching part; one of these latter parts 50 being resilient but only in fore and aft directions.

2. A shoe holder comprising a bar spring having down-turned end portions; a handle secured at a mid-location along it; and a pair of struts, one secured to each end of said spring, for extending in direction toward a plane which is parallel to the axis of the handle; one said strut extending obliquely toward said plane and having a vamp-supporting spreading terminal portion for engaging within the toe of a shoe; the other 60 said strut extending, with less departure from perpendicularity, toward said plane and having a terminal portion for engaging the shoe within its counter; said handle providing stiffness at the mid-part of said spring, and the down-turned 65 portions of spring, between the handle and a strut at each end of the handle, being resilient but only in fore and aft direction; the securing means for spring to at least one of the struts being a detachable connection.

3. A shoe holder comprising a bar spring having downturned end portions; a handle secured at a mid-location along it; and a pair of struts, one secured to each end of said spring, for extending in direction toward a plane which is par- 70 75 916

allel to the axis of the handle; one said strut extending obliquely toward said plane and having a vamp-supporting spreading terminal portion for engaging within the toe of a shoe; the other 5 said strut extending with less departure from perpendicularity, toward said plane and having a terminal portion for engaging the shoe within its counter; said handle providing stiffness at the mid-part of said spring, and the down-turned 10 portions of spring, between the handle and a strut at each end of the handle, being resilient in fore and aft direction; the securing means for spring to at least one of the struts being a detachable connection; there being on each of these 15 parts a lug for engagement in a slot in the other part, each said lug having an angular extension for engaging against the far side of the element through whose said slot the lug extends.

4. A shoe holder comprising a stiff handle and 20 two stiff struts; one of which struts is at the

forward end of the handle, extends obliquely forward and downward, and has a terminal portion for standing within the toe of the shoe, having a top surface for supporting the vamp thereof and having a bottom for engaging against the bottom of the shoe, the relation between the bottom and the top of the terminal portion being such that while the bottom is pressed downward against the interior bottom of the shoe this top can support the vamp sufficiently for external 10 polishing; and the other of which struts extends more directly downward from the handle to engage the interior bottom of the shoe at the heel; the said handle being broad for constituting a grip for holding the toe and heel struts firmly 15 down against the shoe bottom during lateral rubbing of the surface of the shoe; and the said struts and handle being approximately inflexible laterally relative to said terminal portion.
